UNITED STATES PATENT OFFICE.

WILLIAM C. TROCHE, OF AKRON, OHIO, ASSIGNOR TO THE B. F. GOODRICH COMPANY,
OF NEW YORK, N. Y., A CORPORATION OF NEW YORK.

BOOT-TREE.

1,360,059.

Specification of Letters Patent. Patented Nov. 23, 1920.

Application filed July 12, 1920. Serial No. 395,532.

To all whom it may concern:

Be it known that I, WILLIAM C. TROCHE, a citizen of the United States, residing at Akron, in the county of Summit and State 5 of Ohio, have invented a certain new and useful Boot-Tree, of which the following is a specification.

This invention relates to trees or lasts for making boots with high uppers, for example, rubber boots, where the leg part of 10 the tree has to be separated from the fore-part and withdrawn from the boot by a longitudinal sliding movement as distinguished from a hinging or diagonal movement such as is permissible with ordinary 15 shoe lasts.

The object of my invention is to provide a sectional last of which the parts will be firmly secured together, without undue play, 20 while assembled, but which may be readily withdrawn from the boot.

Of the accompanying drawings:

Figure 1 is a vertical longitudinal section 25 of my improved last.

Fig. 2 is a section on line 2—2 of Fig. 1, looking in the direction of the arrows.

Referring to the drawings, 10 is the leg or body of the tree, including the heel portion integral therewith. 11 is the fore-part 30 or foot of the last, divided from the leg or body part 10 by intersecting vertical and horizontal contact planes 12 and 13. The parts are usually made of metal, and as shown are hollow. The vertical face 12 of

35 the leg section 10 is provided with a rectangular registering guide or tongue 14 adapted to inter-fit with and be vertically slidable in a slot or groove 15 in the vertical face of the fore-part 11. Thus the leg-part

40 10 and the foot 11 are adapted for relative vertical movement, while relative lateral movement is prevented by the guide 14 in the slot or groove 15. 16 is a latch hinged to the vertical outer face of the guide 14 by 45 means of a projection 17 on the upper end of said latch which pivotally rests in a recess 18 in said guide 14. 19 is a coil spring extending through a hole 20 in the vertical front wall of the leg-part 10 and the guide 50 14. It is secured at its rear end to a cross-

pin 21 in the heel of the last and at its forward end to a cross-pin 22 extending across an opening 23 through the latch 16. The tension of the spring tends to hold the latch against the guide 14. The lower end 55 of the latch 16 is provided with a cam surface 23 on its inner face adapted to engage automatically a cross-pin 24 in the fore-part 11 when the two parts of the last are assembled by a relative vertical movement, 60 with the guide 14 in the slot 15, the latch in this operation assuming the position shown by the dotted line in Fig. 1, but being returned by the spring 19 to the position shown in full lines when the two parts of 65 the last are brought into contact on the plane 13. The cam surface 23 is so formed that in this assembled position the cam, under the action of the spring 19, holds the two parts, 10 and 11, yieldingly against both 70 relative vertical and fore-and-aft movement.

The guide 14 being rectangular, instead of dovetailed as in certain prior lasts, the spring 19 affords a yielding fore and aft 75 connection, and the coil spring, because of its relatively long range of substantially uniform tension, has advantages over a leaf-spring for this purpose. The latch 16, being hinged or fulcrumed as described, may be 80 made of a single piece of metal, may be cast or forged, and does not require riveting to the body of the last.

I claim:

In a sectional boot tree the combination 85 of fore-part and heel-part members having a vertical tongue-and-groove connection adapted to prevent relative lateral movement of said sections but permit relative vertical and fore-and-aft movement thereof, 90 a latch fulcrumed upon one of said sections and provided with a cam surface adapted to engage a part of the other section, means on said other section to interact with said cam surface, and a spring yieldingly drawing 95 said latch toward the section on which it is fulcrumed.

In witness whereof I have hereunto set my hand this 25th day of June, 1920.

WILLIAM C. TROCHE.
